CLAIM

The ornamental design for a battery housing as shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view of a battery housing.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

(Continued)

The broken lines shown in the drawings depict portions of the battery housing that form no part of the claimed design.
